(57) **CLAIM**

The ornamental design for a pet toy, as shown and described.

DESCRIPTION

FIG. 1 is a perspective view of a first embodiment of the pet toy of my design;

FIG. 2 is a front view thereof;

FIG. 3 is a top plan view thereof;

FIG. 4 is a right side view thereof;

FIG. 5 is a left side view thereof;

FIG. 6 is a rear view thereof;

FIG. 7 is a bottom view thereof;

FIG. 8 is a perspective view of a second embodiment of the pet toy of my design;

FIG. 9 is a front view of the second embodiment of the pet toy of my design;

FIG. 10 is a top plan view of the second embodiment of the pet toy of my design;

FIG. 11 is a right side view of the second embodiment of the pet toy of my design; and,

FIG. 12 is a left side view of the second embodiment of the pet toy of my design; the rear and bottom views of the second embodiment of the pet toy of my design are the same as those shown in FIGS. 6 and 7 respectively.
